ASSIGNORS TO DULUTH REFRIGERATOR CORPORATION, OF DULUTH, MINNESOTA,
A CORPORATION OF MINNESOTA

ICE RACK FOR REFRIGERATORS

Application filed March 6, 1931. Serial No. 520,512.

It is a primary object of the present invention to provide an ice rack for refrigerators which will accelerate the melting of ice through the rack to produce the largest possible exposed ice surface with which air in the refrigerator will contact during its circulation.

Another object of the invention is to provide an ice rack which will function to produce greater melting of the ice at the rear of the rack than at the front so that the resultant depending ice fins will form an inclined surface against which the air contacts in its circulation.

15 A further object of the invention is to provide an ice rack of the character described which is combined with an inclined drip pan to form an inclined passage for the circulation of air in the refrigerator.

20 Other objects of the invention and its advantages will more fully be brought out as the description proceeds.

In the accompanying drawings we have illustrated a practical embodiment of our invention but it is to be understood that the invention may be variously modified without departing from its scope as defined in the appended claims.

25 In these drawings:

30 Fig. 1 is a view partly in side elevation and partly in section of a refrigerator including the ice rack of our invention;

Fig. 2 is a plan view of an ice rack constructed in accordance with our invention;

35 Fig. 3 is a view in front elevation of the ice rack illustrated in Fig. 2;

Fig. 4 is a view in side elevation of our ice rack; and

40 Fig. 5 is a fragmentary sectional view showing the formation of the ice fins.

Referring now to the drawings, the reference numeral 11 indicates a refrigerator which, so far as its general features are concerned, may be of any well-known and desired construction. The refrigerator includes an upper ice compartment 12 and a lower food compartment 13, access to the said compartments being had through suitable doors 14 and 15.

50 The ice and food compartments are sep-

arated by ledges 16 and 17 which extend from side to side of the interior of the refrigerator along the front and rear walls thereof. These ledges are provided with inclined or arcuate surfaces 18 and 19 which function to deflect air circulating within the food compartment 13.

The reference numeral 20 indicates a drip pan which extends from side to side of the refrigerator and is suitably supported therein. This drip pan is, preferably, of hollow construction to provide in its interior a dead air space which functions to insulate the upper and lower surfaces of the pan. As will be noted from Fig. 1, the pan 20 is supported at an angle to the vertical and the purpose of so mounting the pan is to accelerate the circulation of air within the refrigerator. The drip pan is connected to a suitable drain pipe 21.

The present invention relates to the construction of the ice rack which is indicated in the drawings by the general reference numeral 22. As can be seen from Fig. 1, the ice rack is supported upon the ledges 16 and 17. The ice rack is made of suitable metal and comprises front and rear angle-shaped supporting members 23 and 24 which rest upon the ledges 16 and 17 within the refrigerator. In addition to the supporting members, the rack comprises a plurality of cross bars 25 which are connected to the supporting members in spaced relation. As shown in Figs. 3 and 5, the cross bars are of generally inverted U-shape and have the upper webs extended as at 26, the said extensions being secured to the supporting members 23 and 24 in any suitable manner, as for example, by soldering.

Each of the cross members 25 includes two depending sides 27 which as shown in Figs. 1 and 4 are of greater depth at one end than at the other. Preferably, and as hereinafter more fully described, the deeper end of the side members is located at the rear of the refrigerator when the ice rack is in position therein.

The ice rack 22 supports a block of ice 28 within the ice chamber 12. As will be seen from an inspection of Fig. 5, the ice melts

to form fins 29 in the spaces between the cross bars 25. These fins will, in general, be the same shape as the sides of the cross bars; that is to say, the fins will be deeper at the rear than at the front, thus producing an inclined ice surface with which the air will contact in its circulation. The ice surface thus formed is considerably greater than is the surface of the ice exposed to contact with the air where the ordinary form of ice rack is used, that is to say, the form of rack in which the cross bars are of uniform depth.

Our invention is predicated upon the discovery that the ice will melt more rapidly at the point of contact with the metal of the rack than where it is in contact with air only. This is partly due to the pressure of the ice on the rack as well as to the differences in temperature between the metal and the air. 20 Thus, by providing gradually inclined metal surface from the front toward the rear of the rack, we are enabled to accelerate the melting of ice toward the rear of the refrigerator. As a result, a plurality of depending ice fins are formed substantially as shown in Fig. 5, and these ice fins produce a considerably increased ice surface with which the air contacts.

It will be understood, that in a refrigerator such as we have herein disclosed, the circulation of air takes place almost entirely within the food compartment. The air rises upwardly along the front of the refrigerator and is deflected by the inclined surface 18 into the inclined passage between the drip pan 20 and the bottom of the ice and is further deflected by the inclined surface 19 downwardly through the food compartment. Thus, a rapid circulation of air is set up, and in its travel the air contacts with the exposed lower surface of the ice which, by our invention, has been made as large as possible, thereby greatly increasing the efficiency of the refrigerator.

We claim as our invention:

- 45 1. An ice rack comprising a plurality of spaced bars adapted to support a block of ice, said bars being of gradually increased depth toward one end for accelerating the melting of said ice at said end.
- 50 2. An ice rack comprising supporting members, and a plurality of cross bars secured to said members and of gradually increased depth from one end toward the other.
- 55 3. An ice rack for refrigerators comprising supporting members, and a plurality of cross bars secured to said members and of gradually increased depth from the front toward the rear of said rack when positioned in a refrigerator.
- 60 4. An ice rack comprising supporting members, and a plurality of cross bars secured to said supporting members in spaced relation, said cross bars being adapted to support a block of ice and having sides of gradually increased depth from one end to the

other of said rack, whereby ice fins of gradually increased depth are formed in the spaces between said cross bars.

5. An ice rack for refrigerators comprising supporting members, and a plurality of inverted substantially U-shaped cross bars secured to said supporting members, said cross bars having sides of gradually increased depth from the front toward the rear of said rack when positioned in a refrigerator.

6. An ice rack for refrigerators comprising supporting members, and a plurality of cross bars secured to said supporting members, said cross bars having top surfaces lying in a horizontal plane when said rack is positioned in a refrigerator and side walls terminating in edges inclined to the vertical from one end of said bars toward the other, for the purpose specified.

7. In a refrigerator, an ice compartment and a food compartment, a drip pan supported between said compartments, and an ice rack supported above said drip pan, said ice rack having a horizontal top surface for supporting a block of ice and an inclined bottom surface forming with said drip pan an inclined passage for the circulation of air in said food compartment.

In witness whereof, I have hereunto set my hand this 2nd day of March, 1931.

FRED OPHULS.

In witness whereof, I have hereunto set my hand this 13th day of January, 1931.

GEORGE K. NUSS.
